US0D1041510S

(12) **United States Design Patent** (10) **Patent No.:** **US D1,041,510 S**
(45) **Date of Patent:** **** Sep. 10, 2024**

(54) **DISPLAY SCREEN OR PORTION THEREOF
WITH ICON**

(71) Applicant: **HUAWEI TECHNOLOGIES CO., LTD.**, Guangdong (CN)

(72) Inventor: **Xiaoxuan Huang**, Shenzhen (CN)

(73) Assignee: **HUAWEI TECHNOLOGIES CO., LTD.**, Shenzhen (CN)

(**) Term: **15 Years**

(21) Appl. No.: **29/805,887**

(22) Filed: **Aug. 31, 2021**

(30) **Foreign Application Priority Data**

Mar. 2, 2021 (CN) 202130113870.0

(57) **CLAIM**

The ornamental design for a display screen or portion thereof with icon, as shown and described.

DESCRIPTION

FIG. 1 is a front view of a display screen or portion thereof with icon showing our new design according to a first embodiment;

FIG. 2 is a front view of a display screen or portion thereof with icon showing our new design according to a second embodiment; and,

FIG. 3 a front view of a display screen or portion thereof with icon showing our new design according to a third embodiment.

The dash-dot broken lines in the drawings illustrate the display screen or portion thereof and form no part of the claimed design. The remaining dashed broken lines in the drawings illustrate portions of the icon that form no part of the claimed design.

1 Claim, 3 Drawing Sheets
